Attorney.

UNITED STATES PATENT OFFICE

SAMUEL A. NEIDICH, OF EDGEWATER PARK, NEW JERSEY

METHOD OF AND MEANS FOR MAKING TUBES OF CELLULOID AND THE LIKE

Application filed March 13, 1929, Serial No. 346,789. Renewed July 30, 1932.

My invention may be employed with particular advantage in the manufacture of tubes for fountain pens and similar writing implements, from cellulose products such as celluloid, cellulose nitrate, cellulose acetate, or any suitable substance, by rolling thin sheets of such material, in evolute form, with the convolutions thereof in contact with each other, while moistened with a suitable solvent. For instance, acetone is a suitable solvent for celluloid and cellulose nitrate, and ethyl acetate, or a mixture of alcohol and ether, are suitable solvents for cellulose acetate.

Such sheets are made by shaving solid molded blocks of such materials, and the commercial sheets vary in thickness from the standard nominal size thereof. For instance, sheets which are supposed to be .010 of an inch thick vary from .009 of an inch to .011 of an inch. Consequently, in the manufacture of tubes, it is necessary to cut the sheets, for rolling, long enough to form the desired thickness of the tube if the material be of the abnormal minimum thickness aforesaid and if the sheet be of the proper thickness or in excess thereof, as above contemplated, the resultant tube is thicker than required and must be reduced in size.

Therefore, it is the purpose and effect of my invention to provide means for reducing the rolled tubes to a predetermined size and shape by wiping the surplus material, with a blade-like gauge element, during the winding of the last convolution upon the tube. Such wiping may merely spread the material of the tube, to change the shape of the latter, or scrape off the surplus material.

As hereinabove described, the gauge element may not only be adjusted to predetermine the diameter of the cylindrical tube required, but may be so shaped as to form other configurations; for instance, the ends of fountain pen bodies opposite to that in which the pen point is inserted are made conical to readily detachably fit a removable cap for the point, and my present invention is adapted to produce such conical configuration contemporaneously with the reduction of the rolled tube to the proper diameter.

My invention includes the various novel features of procedure and apparatus herein-after more definitely specified.

In said drawing; Fig. I is a fragmentary vertical transverse sectional view of a machine for forming tubes by rolling a primarily plane sheet of cellulose product. 55

Fig. II is a sectional view similar to Fig. I but showing a modified form of tube scraping means. 60

Fig. III is a vertical transverse sectional view of another modified form of machine, including means for measuring successive charges of solvent for introduction to the solvent container in which the tube is rolled. 65

Fig. IV is a perspective view of a sheet of the material aforesaid adapted for temporary engagement in any of said machines.

Fig. V is a perspective view of the scraper blade and its adjusted means indicated in 70 Fig. III.

Fig. VI is a side elevation of a mandrel carrying a tube in cooperative relation with a blade which is of such configuration as to reduce one end of the tube to conical form, 75 while reducing the other portion of the tube to a cylindrical form and predetermined diameter.

In said figures; a suitable sheet of material 1 is attached at its lower end upon a mandrel 2 which is conveniently flattened at its end 3 for engagement in a head stock 5 provided with a manually operative crank handle 6 or any other means by which it may be rotated. The opposite end 8 of said mandrel is detachably fitted in a tail stock 9, in axial alignment with said head stock. One of said stocks may be axially adjustable and spring pressed toward the other, so that the operator may move one of said stocks to insert and remove a succession of mandrels provided with sheets as in Fig. IV. 80 85

Referring to the form of my invention shown in Fig. 1; the solvent bath 10 is held in the container 11, conveniently a rectangular box of Monel metal in the opposite side walls of which said stocks 5 and 9 are journaled. The gauge element 13, which may be a scraping blade, is detachably secured, conveniently by screws 14, upon the swing frame 95 100

15 which is hung upon the shaft 16 extending parallel with the axis of said stocks. The spring 17 which encircles said shaft 16 tends to press the forward edge 19 of said blade 13 against the surface of the tube 20 which 5 is formed by rolling the sheet 1 as above described. However, said blade 13 may be adjusted to predetermine the precise diameter of the finished tube 20, by means of the screw 22 which is in threaded engagement with the cross bar 23 and clamped in adjusted position by the nut 24. Such construction and arrangement permit the blade 13 to yield, and swing radially outward from the axis of rotation of the tube 20, during the operation 10 of removing the surplus material from the tube. However, in some cases, I prefer to have the position of the blade positively maintained during such operation of determining the size of the tube. For instance, in 15 Fig. II, the gauge element 26 is detachably secured, conveniently by screws 27, upon the swing frame 28 which is hung upon the shaft 29 extending parallel with the axis of the mandrel 2 and adapted to be adjusted by the screw 31 which is in threaded engagement with the side wall of the container 32 for the solvent and secured in adjusted position by the nut 34 and the lock washer 35.

20 In the form of my invention shown in Fig. III, the container 35 for the solvent 36 has the stationary cross bar 37 supporting the gauge element 38 by a pair of bolts 39 which extend thru respective slots 40 in said blade 25 and are clamped by nuts 41. As indicated in Fig. V; said slots 40 are inclined with respect to the edge of the blade 38 so that when said nuts 41 are loosened, said blade may be 30 adjusted toward and away from the axis of the mandrel 2 by moving it in respectively 35 opposite directions. Such movement is conveniently effected by adjusting a pair of screws 43 which are mounted in screw threaded engagement with the opposite end 40 walls of said container 35. Said blade is secured in adjusted position by tightening the wing nuts 41.

45 In the form of my invention shown in Fig. III; the container 35 has the outlet conduit thru which the solvent 35, which is 50 charged with material dissolved from the sheets 1, may be discharged under control of the valve 46. The level of the solvent 36 in said container 35 is determined by the location of the overflow port 47 which communicates with the conduit 48 leading to said discharge conduit 45, beyond said valve 46. The solvent 36 may be supplied to said container 35 in successive charges, each of a 55 measured quantity, by the means shown in Fig. III, including the measuring receiver 49 which is conveniently provided with the sight gauge 50 and to which the liquid solvent 36 is supplied thru the conduit 51 under 60 control of the valve 52. The rotary valve 53

has the passage 54 which, in the position shown, connects said conduit 51 with the conduit 55 leading into the bottom of the receiver 49; so that the latter may be charged with any desired quantity of said solvent 36. 70 Thereupon, the valve 52 is closed and the valve 53 turned contra-clockwise, thru an angle of 90°, to cause said passageway 54 to establish communication between the conduit 55 and the conduit 56, leading into the container 35. When thus turned; the measured quantity of the solvent is discharged from the receiver 49 into the container 35 and may be sufficient to fill the latter to the level indicated in Fig. III, or otherwise. 75

80 For instance, with the valve 53 in the position shown in Fig. III, the valve 46 may be opened to either entirely discharge or partially discharge the solvent 36 from the container 35 and, when the valve 46 is closed, the valve 53 may be turned to discharge the measured quantity of the solvent from the receptacle 49 into the container 35 to either entirely or partly refill the latter.

85 As indicated in Fig. VI; the gauge element 57 has its edge 58 so shaped as to reduce to conical form the end portion 60 of the tube 61 while the latter is mounted on a mandrel 2, in such mechanism as shown in Figs. I or II. As above explained, that 90 form of tube 60 is adapted for making bodies of fountain pens.

95 Therefore, I do not desire to limit myself to the precise details of procedure and apparatus above described, as it is obvious that 100 various modifications may be made therein without departing from the essential features of my invention, as defined in the appended claims.

105 I claim:

1. Means for forming tubes of celluloid and the like, including a mandrel holder for such material, and means adapted to roll a sheet of such material on said mandrel holder; a gauge member mounted substantially parallel with the axis of said holder; and means adapted to adjustably determine the position of said gauge member with respect to said axis; whereby said gauge member is adapted to deform the outer surface of said tube; including a screw adapted to shift the position of said gauge by its rotation.

110 2. Means for forming tubes of celluloid and the like, including a mandrel holder for such material, and means adapted to roll a sheet of such material on said mandrel holder; a gauge member mounted substantially parallel with the axis of said holder; and means adapted to adjustably determine the position of said gauge member with respect to said axis; whereby said gauge member is adapted to deform the outer surface of said tube; including a slot in said gauge member, inclined with respect to the axis 115 120 125 130 135 140 145 150

of said mandrel holder; gauge supporting means extending through said slot; and two screws, respectively at opposite ends of said gauge member and adapted to shift the position of said gauge by their relative rotation.

3. Means for forming tubes of celluloid and the like, including a mandrel holder for such material, and means adapted to roll a sheet of such material on said mandrel holder; a gauge member mounted substantially parallel with the axis of said holder; and means adapted to adjustably determine the position of said gauge member with respect to said axis; whereby said gauge member is adapted to deform the outer surface of said tube; including a pair of parallel slots in the gauge member inclined with respect to the axis of the mandrel holder, and supporting means for said gauge member including a stationary bar, clamping bolts projecting from said bar through said slots, and nuts adjustable on said bolts to clamp said gauge member in rigid relation with said bar.
- 25 4. A method of forming a tube of celluloid and the like to a predetermined size and form by rotating it in a liquid solvent of the material thereof while deforming the outer surface of said tube by the wiping scraping action of a gauge element maintained in predetermined radial relation to the axis of rotation of said tube.

In testimony whereof, I have hereunto signed my name at Burlington, New Jersey,

35 this 31st day of January, 1929.

SAMUEL A. NEIDICH.
